UNITED STATES PATENT OFFICE

EMIL L. NUEBLING, OF READING, PENNSYLVANIA, ASSIGNOR TO READING METER REPAIR COMPANY, OF READING, PENNSYLVANIA, A CORPORATION OF PENNSYLVANIA

SERVICE-PIPE CURB BOX

Application filed June 6, 1927. Serial No. 196,770.

This invention relates to improvements in curb boxes, and has for its objects to provide a box, and more particularly a cover therefor, which will remain at its proper position with respect to the surface of the adjacent ground, even when the latter is subjected to freezing temperature.

A further object is to provide means associated with the cover to rigidly clamp it in position in the extremity of the box, and at the same time, facilitate its swift and convenient removal.

Another object is the provision of a cover for curb boxes which when applied, will completely close the extremity of the box against the admission of dirt or other foreign matter.

A still further object is the selection of appropriate materials for the manufacture of the various parts of the box, and cover, so as to assure at all times, convenient removal of the cover.

With the foregoing objects outlined and with other objects in view which will appear as the description proceeds, the invention consists in the novel features hereinafter described in detail, illustrated in the accompanying drawings, and more particularly pointed out in the appended claim.

Referring to the drawings,

Fig. 1 is an elevation of the cover and locking means, removed.

Fig. 2 is an enlarged section of the upper extremity of the box showing the cover applied.

Fig. 3 is a perspective view partly in section of the upper part of the curb box.

Fig. 4 is a plan development of the interior of the box.

Referring to the drawings in detail, the numeral 5 indicates the body of the box provided as usual with the helical groove 6. Internally at its upper extremity, the box is provided with two opposed spiral ribs 7, extending downwardly a comparatively short distance within the box, and terminating at their upper extremities in flanges 8 lying at the opposite sides of the box, and in the same circumferential plane, so as to present a seat for the cover, indicated at 9.

The medial central portion of the cover is depressed as at 10, and is provided peripherally with a flange 11, adapted to be seated upon the segmental flanges 8, constituting a seat therefor. The cover 9 is provided centrally with an aperture 12, receiving the flanged portion 13 of a stem 14, the adjacent portion of which is received at the reduced lower extremity 15 of the aperture 12, so as to limit the downward thrust of the stem, relative to the cover. The flange 13 and reduced portion of the stem are of cylindrical form, whereas the lower extremity 14^a thereof is polygonal and received within an opening 16 of the locking lever 17, the extremities of which latter are headed as at 18, and adapted to be threaded into the grooves defined between the helical ribs or flanges 7, during the rotary motion thereof. The locking lever 17 is held in place on the stem by a locking pin 19, passed diametrically through the stem, whereas the extreme upper extremity of the latter is of polygonal form to provide a head 20 adapted to receive a suitable type of wrench to facilitate turning of the stem and locking lever. The stem is of such construction as to permit of a limited amount of play between the locking lever and the cover.

It will be observed that the upper part of the curb box is of uniform diameter throughout, and the external surface thereof, except for the groove 6, is of plain cylindrical form, while the cover 9 lies wholly within the external dimensions of the box. This is an important feature of the invention, as on occasions when the earth surrounding the box is frozen and expands above the normal level, it can readily slip over the smooth external surface of the box without resting on the latter, and thus, when the surface level of the ground recedes to its normal position, the top of the box is in its proper position, and is not raised above the surface of the ground, as frequently occurs with types of curb boxes now in use.

The cover 9 may be inexpensively cast from iron, whereas the locking lever 17 is preferably of wrought iron. The stem 14, however, is preferably made of brass or some such

equivalent material which is not affected by the action of the elements.

For the purpose of raising or lowering the box, in cases where the level of the surrounding ground is altered, slots 21 are formed in the segmental seat flanges 8 for receiving a suitable flat tool to permit adjustment of the top section of the box.

In removing the cover, the first operation of the stem, when turned in the proper direction, is to release the tension clamping the cover in position. Upon further turning of the key, an upper pressure is exerted upon the cover, which, with the assistance of tappings, will lift the lid clear of the seat flanges, and free from the box.

From the foregoing it is believed that the construction, operation and advantages of my invention may be readily understood, and I am aware that changes may be made in the details disclosed without departing from the spirit of the invention as expressed in the claim.

What I claim and desire to secure by Letters Patent is:

In combination, a cylindrical curb box having an inner surface provided adjacent its upper end with a cover seat and spaced opposed helical flanges extending beneath said seat, a centrally apertured cover adapted to rest on said seat, a stem extending rotatably and slidably through said aperture and having a flange thereon resting on the upper side of the cover, arms fixed to and extending laterally from the stem a distance sufficient to interengage with said helical flanges, said arms being located a distance beneath the cover sufficient to permit appreciable relative sliding movement between the cover and stem.

In testimony whereof I affix my signature.
EMIL L. NUEBLING.
